UNITED STATES PATENT OFFICE

121,394

DESIGN FOR A PHOTO ENLARGING MASK

Henry W. Lormor, Cleveland Heights, Ohio

Application December 7, 1939, Serial No. 88,756

Term of patent 3½ years

To all whom it may concern:

Be it known that I, Henry W. Lormor, a citizen of the United States and a resident of Cleveland Heights, in the county of Cuyahoga and State of Ohio, have invented a new, original, and ornamental Design for a Photo Enlarging Mask, of which the following is a specification, reference being made to the accompanying drawings, forming a part thereof, in which

Fig. 1 is a perspective view of a photo enlarging mask in closed position showing my new design; Fig. 2 is a vertical sectional view along the line

2—2 of Fig. 1 showing more clearly the contour and appearance of my design; and

Fig. 3 is a perspective view of the same mask in open position showing further the appearance and design of the several elements of the article.

It will be seen that the upper part of the frame consists of an open framework, while the lower part is solid.

I claim:

The ornamental design for a photo enlarging mask, substantially as shown and described.

HENRY W. LORMOR.
